FIG. 1 is a perspective view of a baton.

FIG. 2 is a right elevation view of the baton of FIG. 1.

FIG. 3 is a left elevation view of the baton of FIG. 1.

FIG. 4 is a front elevation view of the baton of FIG. 1.

FIG. 5 is a rear elevation view of the baton of FIG. 1.

FIG. 6 is a top plan view of the baton of FIG. 1; and,

FIG. 7 is a bottom plan view of the baton of FIG. 1.

The broken lines depict portions of the baton that form no part of the claimed design.
